UNITED STATES PATENT OFFICE.

WILLIAM WORTH JACKSON, OF BETHANY, LOUISIANA.

HULLER, CLEANER, AND SEPARATOR.

SPECIFICATION forming part of Letters Patent No. 293,029, dated February 5, 1884.

Application filed June 16, 1883. (No model.)

To all whom it may concern:

Be it known that I, WILLIAM WORTH JACKSON, of Bethany, in the parish of Caddo and State of Louisiana, have invented a new and 5 Improved Huller, Cleaner, and Separator, of which the following is a full, clear, and exact description.

The object of my invention is to provide a simple, durable, and effective machine for 10 stripping or clearing the hulls or pods from peas, beans, and the like.

Reference is to be had to the accompanying drawings, forming part of this specification, in 15 which similar letters of reference indicate corresponding parts in all the figures.

Figure 1 is a side elevation of my improved machine. Fig. 2 is a central longitudinal sectional elevation of the same, and Fig. 3 is an elevation of the reverse side of the 20 machine to that shown in Fig. 1. Fig. 4 is an end elevation, showing the relative position of the outlets for the pods or refuse and for the peas or beans.

On or in any suitable main casing, *a*, supported on legs *a'* or otherwise, I fix the case *b* for the thrashing or hulling cylinder *c*, which is journaled suitably in case *b* to revolve therein. The cylinder *c* consists of any suitable wheel rim or tube built up of wooden staves, 30 if desired, and armed with spikes or teeth *c'*, which revolve past or between the spikes or teeth *b'* of the stationary divided case *b*, the lower half of which latter case is in this example of my invention fixed to the main casing *a*, and the upper half being arranged to lift off with the hopper *e* for access to the cylinder *c* and the hulling-teeth *b'* *c'* when necessary to clean, adjust, or repair the parts. The 35 hopper *e* is fitted with a valve or slide, *f*, which may be adjusted to open or close its throat *g*, for feeding the peas, beans, &c., to the hulling-cylinder and case as fast as desired, and as the cylinder *c* revolves in the direction of the arrow the peas from the hopper are carried 40 quite around by the cylinder, which strips the hulls off and discharges most of them clear of the machine through the opening *h*, made for the purpose in the side of case *b*, while the hulled peas or beans fall between the teeth *b'* *c'* and through suitable openings, *i*, at the

bottom of case *b*, upon a sloping shaker or shoe, *k*, which is pivoted suitably to casing *a* at *l*, and is alternately raised and let fall by an angular or cranked shaft, *m*, journaled in a casing, *a*, and while the peas roll down shoe 55 *k* they receive the air-blast from a fan-blower, *n*, journaled by its shaft *n'* in any approved case, *o*, having suction-openings *o'* at one or both ends for inlet of air to the fan, the air-outlet therefrom being arranged to direct the 60 blast upon the shaker *k*, to drive off any hulls or light trash which may fall thereon from the case *b*, while permitting the hulled and cleaned peas or beans to descend to a discharge-spout, *p*, for delivery into any suitable receptacle. 65

It will be perceived by the arrow in Fig. 1 of the drawings that the peas or beans are carried down to the bottom around to the hole *i*, where the heaviest and finest matters—that is, 70 the peas or beans with the broken pieces of the pods—are discharged, and the haulm or vine with the larger pieces of pods are then carried up to the opening *h*, where they are for the most part discharged beyond the upper 75 edge of the sieve. Any haulm or pods which pass the hole *h* will be again carried around, become more thoroughly broken up, and ultimately pass out at one of the openings *h* *i*. The peas or beans falling on the wire-screen 80 shaker-shoe *k* are shaken, so that the dirt, dust, or other adhering matter may be detached and caused to pass through the screen, and as they roll down the inclined shoe they are met by a blast, which carries to and over the rear 85 of shoe any pieces of pod or haulm which may have passed through the opening *i* with the peas or beans. In this example I apply the driving power by a hand-crank, *q*, on the shaft of cylinder *c*, which has a belt-pulley, *r*, over which a belt, *s*, travels to the pulley *t* on the shaft *m* to work the shaker *k*, and at the other side of the machine the large pulley *u* on the cylinder-shaft runs the belt *v*, which 90 drives the small pulley *w* on the shaft *n'*, for imparting the necessary speed to the fan-blower *n*. 95

If desired, the shaker *k* may be a wire screen of suitable mesh to permit small heavy waste 100 matters and dust or sand to pass freely through

it, to insure a better separation and cleaning of the product.

Instead of discharging the cleaned peas or beans from shaker *k* into spout *p* at the end 5 of case *a*, I may extend the lower wall, *o'*, of the air-passage farther toward the case *b* and shorten shaker *k*, and pass its lower end through an opening in the bottom of the case *a*, near shaft *m*, for discharging directly from the 10 shaker into any suitable vessel below it.

Thus constructed and arranged, my improved machine may be cheaply built, is well calculated for durability in use, and will effect a large saving in time and labor in preparing 15 peas and beans for market, and the machine may be built of any size or capacity desired.

I am aware that it is not new to make the teeth of the rotary cylinders of thrashers to interlap with teeth on the concave; also, that

the stationary case has been made in two parts, 20 so that the upper may lift off with the hopper; also, that a slide-valve has been used in hoppers to regulate the feed; but

What I do claim as new and of my invention is—

In a pea or bean huller, the combination 25 of the fan, the inclined sieve, the rotary toothed hulling-cylinder, and the stationary toothed case, the latter provided with an opening near the bottom to intercept the smaller matters 30 and discharge them on the sieve, and an opening at the side for discharging the vines beyond the end of the sieve, substantially as shown and described.

WILLIAM WORTH JACKSON.
